CHARLES A. COUCH AND SAMUEL P. HATCHER, OF WARE SHOALS, SOUTH CAROLINA,
ASSIGNORS TO WARE SHOALS MANUFACTURING COMPANY, OF WARE SHOALS,
SOUTH CAROLINA, A CORPORATION OF SOUTH CAROLINA.

AUTOMATIC STOP FOR SEWING MACHINES.

Application filed March 30, 1928. Serial No. 265,936.

This invention relates to an attachment for sewing machines, more particularly machines employed in hemming pillow cases and the like, whereby the machine will be 5 automatically and promptly stopped whenever from the breaking of the thread or other cause the hem is not being sewed.

In the manufacture of certain articles, such for example as pillow cases, it has long 10 been customary to first cut or tear the material into the necessary lengths, then to fold and seam one side and one end thereof, and finally to hem the open ends.

We have sought to improve upon such 15 practice, and thereby to reduce the cost of manufacture, by first hemming the material in the piece, before it is cut up into lengths and folded. To this end, a bolt of cloth is run from a roll through a sewing machine, 20 which folds and stitches the hem on one side of the piece, and thence to a folding device by which the hemmed piece is piled up in folded lengths. Much trouble and delay was, however, experienced in stopping the 25 machine whenever, due to a breakage of the thread or otherwise, the folded hem was not being properly sewed down and in returning the piece to the point at which the failure occurred, especially as the failure might 30 not be noticed for some time in case the machine was not being closely watched. Our present invention, by providing a means for 35 stopping the machine before a piece has been carried more than a few inches beyond the point of failure, has not only largely obviated this difficulty but also makes it possible to run the machine at a higher speed and with less care and attention than was otherwise practicable.

40 The new stop attachment comprises, briefly stated, a detector movably mounted to ride upon the material being hemmed at a point slightly behind the needle of the machine, which detector normally bears lightly 45 against and is held by the edge of the hem and is operative whenever the hem is not being sewed down to slide forward within the hem, and means controlled by such movement for shutting down, or disconnecting, 50 the power used to drive the machine.

One practical embodiment of the invention is shown, by way of illustration and not

of limitation, in the accompanying drawings, in which—

Figure 1 is a perspective view of a sewing 55 machine equipped with the new stop attachment as applied to effect the release of a lever employed to actuate, and to hold in, the clutch by which both the sewing machine and a folding device (not shown) are operatively coupled to a power shaft, showing the detector in normal position bearing against the edge of a hem; Fig. 2 is a view similar to Fig. 1 but showing the position assumed by the parts when the detector has 60 moved within the hem when left unsewn; and Fig. 3 is an enlarged detail, also in perspective, of the clutch-lever holding and releasing mechanism.

Referring to the drawings, 5 indicates a 70 standard, or any suitable, sewing machine, and 6 a portion of the piece of cloth which is being hemmed thereon; and 7 is the upper end of the lever which, as customary, controls a clutch (not shown) by which both the 75 sewing machine and the mechanism (also not shown) for feeding the piece of goods and as hemmed piling it up in folded lengths are operatively connected with and disconnected from the power shaft. To throw in 80 the clutch, to start the machine and associated mechanism, the clutch-lever is swung, to the right as shown, to a substantially vertical position and is there held by a catch 8 which is mounted to slide in guides in a bed- 85 plate 9 and is pressed back against the action of a spring 10 by the engagement of the lever with its inclined outer end 11 as the lever is swung up and then springs out behind it to lock it in place. On the withdrawal of the 90 catch, the lever is released and is swung back, as by a suitable spring (not shown) and thereby throws out the clutch and stops the machine.

In the specific embodiment here shown, 95 the withdrawal of the catch, to release the clutch-lever and throw out the clutch, is automatically effected under the control of a detector which is in turn controlled by the operation of the machine, as follows:

The detector 12, with end 13 tapered and beveled to a blunt point, is secured to and carried at the end of the depending forward arm of a bent rod 14, which is support-

ed and slides in a notch 15 in the lower side of an open slot in a bracket 16 secured in any suitable manner, preferably adjustably, to the head of the machine. Fixed to the rod 5 14, adjoining the bend therein, is an additional shorter bent rod 17 providing a spaced parallel length which slidingly bears in a notch 18 in the lower side of a second slot in the bracket 16 and serves not only to reinforce the rod 14 but to hold its dependent arm substantially perpendicular and so prevents the detector from being shifted laterally by its contact with the moving piece of material upon which, thus slidingly supported, it rides lightly. At its other or rear end 10 the rod 14 is connected, at 19, to one arm of a bell-crank 20 pivotally mounted by a stud 21 on a shaped bracket 22, secured to the upright standard of the machine, which 15 provides at its upper side a projecting stop-lug 23 and at its lower side a lug 24 to which is attached a light spring 25 connected at its other end to the downwardly depending arm of the bell-crank. The upper arm of 20 the bell-crank is in turn connected by a link 26 to the end of an arm 27 with shaped head 28 pivotally mounted at 29, to swing its head into and out of the path of a cam 30 which 25 is made as an integral part of or is suitably attached to the fly-wheel of the machine, upon an ear or lug 31 carried at right angles thereto by a lever 32 pivotally mounted at 33 on a shaped bracket 34 also secured on the upright standard of the machine. The 30 lower end of the lever 32 is operatively connected by a link 35 with a trip-lever 36 which is pivoted at 37 on the bed-plate 9 and has a rounded outer end operatively bearing against a lug or shoulder 38 carried by the 35 catch 8.

In operation, on starting the hemming of a piece of goods, the detector is moved outwardly and set with its point bearing against the edge of the hem, thus raising the head 40 of the arm 27 out of the path of the cam on the fly-wheel, and it will be so held and will in turn hold the arm in inoperative position as long as the hem is being properly sewed down. Should the thread break, however, or should the machine cease to function 45 properly, as where the line of stitches runs off the edge of the hem for instance, the end of the detector will at once be drawn within the folds of the unsewn hem, by action of the 50 spring 25, and the head of the arm 27 will drop into the path of the cam on the fly-wheel of the machine. Thereupon, on the first revolution of the fly-wheel, the cam will engage the head of the arm 27 and, moving 55 it outwardly, will throw out the upper end of the lever 32, which in turn will swing the trip-lever 36 to force back the catch 8 and release the clutch-lever.

It will be seen that the power required for 60 the withdrawal of the catch, to release the

clutch-lever, is supplied by the machine itself. The detector merely serves by its position to control the position of the arm 27. Hence, the pressure with which the point of the detector is held against the edge of the hem is merely sufficient to insure the required movement of the detector in case of a failure. The spring 25 may therefore be omitted, if desired, as the weight of the arm 27 will usually be, or may be made, sufficient for the 75 purpose.

A device constructed substantially as herein shown and described has been found effective, in use, to stop the machine and associated feeding mechanism when running at 80 the usual high speed before the piece of goods has been carried more than a few inches beyond the point at which a failure to properly stitch the hem occurs.

It is obvious that the attachment can be 85 used without substantial change to actuate the control switch of an electric motor drive, and, further, that the invention can be variously modified in its several details, within the scope of the appended claims, without departing 90 from the spirit or sacrificing the advantages thereof.

What we claim as new, and desire to secure by Letters Patent, is—

1. A stop device for use in connection with 95 a power-driven sewing machine, comprising means adapted to be actuated by the machine and when so actuated to effect the shutting off of the power driving the machine and means normally bearing laterally against an 100 edge of the piece of goods being sewed on the machine and controlled by the proper stitching thereof for controlling the said power-control means.

2. A stop attachment for sewing machines, 105 comprising a movably mounted member normally biased to a position to be acted upon by a movable part of the running machine and operative when acted upon thereby to effect the shutting off of the power driving the 110 machine, and for the control thereof a member slidably mounted to bear against the edge of the hem of a piece of goods being sewed upon the machine to be held thereby and in turn to hold said member out of operative position and operative on the failure of the machine to sew the hem to shift between the folds of the hem and thereby release said member. 115

3. A stop attachment for power-driven sewing machines, comprising, in combination 120 with means normally operative to effect the shutting off of the power driving the machine, a detector slidably mounted to ride upon the piece of material being hemmed on the machine, means normally holding the 125 point of the detector against the sewed edge of the hem and effective to shift the same within the hem whenever left unsewed, and connections controlled by the detector whereby the power controlling means will be held 130

inoperative so long as the point of the detector is held at the edge of the hem and will be released to shut off the power when the point of the detector is shifted into the hem.

5. 4. In a device of the character described, the combination, with a power-driven sewing machine, of a movably mounted member adapted by a shift in its position to effect the shutting off of the power driving the machine, an element movably mounted upon said member and normally biased to position to be acted upon by a cam on the fly-wheel of the machine to shift the position of the member to shut off the power driving the machine, and means for controlling said element comprising a detector slidably mounted in position to bear against the edge of the hem of a piece of goods being sewed upon the machine and as held thereby to hold the element out of operative position and means

10

15

20

adapted to shift the detector within the folds of the hem when not being properly sewed to thereby release the element.

5. In a device of the character described, the combination, with a power driven sewing machine, of a spring catch adapted to releasably lock in place a lever by which the sewing machine is operatively connected with a power shaft, a movably mounted member normally biased to a position to be actuated from the fly-wheel of the machine to withdraw the catch and release the lever, and means adapted to bear laterally against the edge of the hem of a piece of goods being hemmed on the machine and to hold said member out of operative position so long and only so long as the hem is being sewed.
